UNITED STATES PATENT OFFICE

WILLIAM G. PRICE, OF PITTSBURG, PENNSYLVANIA.

SLACK-ADJUSTER.

No. 818,641.

Specification of Letters Patent.

Patented April 24, 1906.

Application filed February 11, 1905. Serial No. 245,310.

To all whom it may concern:

Be it known that I, WILLIAM G. PRICE, a citizen of the United States, residing at Pittsburgh, in the county of Allegheny and State of Pennsylvania, have invented certain new and useful Improvements in Slack-Adjusters; and I do hereby declare the following to be a full, clear, and exact description of the invention, such as will enable others skilled in the art to which it appertains to make and use the same.

This invention relates to improvements in brake-rigging for car-trucks, and more particularly to slack-adjusting devices therefor.

The object in view is the provision of means for automatically taking up slack produced by the wear of brake-shoes; and this object is accomplished by the provision of a movable element interposed between the brake-shoes and designed to be moved in one direction for taking up the wear of such shoes and a plurality of relatively small objects designed to be moved into the path of movement of said movable element for preventing a return stroke thereof.

The invention further involves the conception of taking up the wear not only of brake-shoes, but also of any mechanical elements by the employment of separable devices and relatively small articles adapted to be moved between said devices for maintaining the same spaced apart, said devices being designed to be connected with the wearing parts for taking up the slack produced by the wear thereof.

With the above-mentioned and other objects in view the invention further comprises certain novel constructions, combinations, and arrangements of parts, as will be herein-after fully described and claimed.

In the accompanying drawings, Figure 1 represents a view, partly in elevation and partly in section, of a slack-adjusting device embodying the features of the present invention and illustrated as applied to a car-truck. Fig. 2 represents an enlarged detail longitudinal section through the slack-adjuster proper.

The present invention relates generally to the type of devices disclosed by my former application for Letters Patent, designated by Serial No. 186,399, filed by me on the 23d day of December, 1903, the invention being especially applicable to car-brakes, but clearly involving a scope including any mechanical

devices wherein it is desirable to take up slack produced by wear or otherwise.

Referring to the drawings by numerals, 11 indicate the ordinary supporting-wheels of a truck, carrying the axles 2, each of which axles support the ordinary bearing-box 3, the bearing-boxes 3 being inclosed by side frames 4, and an equalizer-bar 5 being interposed between the boxes 3 upon each side of the truck. As each side of the truck is made exactly like the other, I have illustrated but one side of the truck, and by reference to Fig. 1 it will be seen that a bracket 6 is fixed to the equalizer-bar 5 near each end thereof and extends upwardly and overhangs the corresponding brake-beam 7. A link 8 is pivotally connected at its upper end to the upper end of each of the brackets 6 and extends to and pivotally engages a lug 9, extending upwardly from the corresponding brake-beam 7, whereby the brake-beams 7 are supported by the equalizer-bars 5 and are left free to swing substantially horizontally; but in carrying out the present invention I find it desirable to prevent too free swinging of said brake-beams, and I therefore interpose between the nut 10 of bolts 11, pivotally connecting the link 8 with the bracket 6, and said bracket a spring 12, which produces friction and frictionally resists pivotal movement of the link 8 with respect to the bracket 6 when the nut 10 is threaded home. The spring 12 of course makes possible the maintaining of any desired degree of friction. The bolt 13 forms the pivotal connection between the lower end of the link 8 and the lug 9, and a coil-spring 14 surrounds said bolt 13 and is adapted to be engaged by the nut 15 for producing friction in a manner similar to the action of the spring 12 above mentioned.

In operation the friction of the pivots of the links 8 is maintained at preferably a high degree for insuring the brake-beams 7 remaining at any given adjusted position. The structures above mentioned are all clearly set forth in my former application, Serial No. 186,399, above referred to, and constitute no part of the present invention and are not claimed herein.

Each of the brake-beams 7 carries at each end a bracket 16, supporting at its free end a brake-shoe 50, positioned for engaging the respective wheel 1. Arranged, preferably, centrally of the length of each of the brake-beams 7 is a bifurcated bar 17, which is fixed to the respective beam, extends outwardly

therefrom, and pivotally engages a brake-lever 18, each of the bars 17 being formed with a chamber 19, containing a spring 20, engaging the respective bar 17 at one end and the 5 respective lever 18 at the other, said spring 20 serving to take up the wear between the respective lever 18 and its pivotal connection with the bar 17. The truck illustrated in the accompanying drawings, to which the 10 disclosed embodiment of the present invention is applied, is provided with a transom 21 at each side and a centrally-arranged bolster, as is usual in this type of truck, and a bracket 22 extends upwardly from one of the transoms 21 and is pivotally engaged by link 23, which link extends to and is pivotally connected with the upper end of one of the levers 18. The other lever 18 is pivotally engaged by any preferred form of draft apparatus 24, which may be connected in any preferred manner and operated as desired for swinging the lever 18. The levers 18 extend below their pivotal connection with the bars 17 and at their lower ends are pivotally connected together by means of an expanding adjuster, (seen in detail in Fig. 2,) said adjuster being designed to convey movement from the lever connected with the draft apparatus 24 to the opposite lever for purposes 25 hereinafter mentioned.

The expanding adjuster connecting the lower ends of the levers 18 consists of longitudinally-separable elements and means for maintaining such elements in their separated 30 condition as long as desired. More specifically, said expanding adjuster consists of an arm 25, pivoted, as at 26, to the lower end of one of the levers 18 and carrying a casing 27, provided with internal chambers or longitudinal cavities 28 and 29, and a rod or plunger 30 extends into the chamber 29 and is longitudinally movably mounted therein, a bar 31 being rigidly fixed to the rod 30 and pivotally connected, as at 32, to the lower end of 35 the lever 18 opposite the lever pivotally engaging arm 25. The arm 25 carries at its free end a casing 33, carrying a spring 34, engaging the lower end of the respective lever 18 and pressing the same toward the pivot 26 for taking up the wear between the lever and 40 pivot. A cap 35, similar to the cap 33, is carried by the bar 31, and a spring 36 is carried by said cap and engages the lever 18 for pressing the same toward pivot 32 for taking 45 up wear between the parts. A relatively small aperture 37 is formed in the partition between the chambers 28 and 29, and near the end of the chamber 29 is formed a relatively large aperture 38, the aperture 38 registering with an aperture 39, formed in the lower wall of the casing 27. A plug-valve 40 extends through the apertures 39 and 38 and is bored longitudinally, as at 41, the diameter of the bore 41 being preferably several times 50 greater than the diameter of aperture 37.

The valve 40 is formed with a lateral bore 42, communicating with bore 41, for purposes hereinafter mentioned. The lower end of the valve 40 projects beyond the wall of the casing 27 and may be provided with a poly-sided portion for receiving a rotating tube. The valve is further transversely apertured to one side of its axis for receiving a pin 44, the pin 44 also extending through the casing 27 for locking the valve 40 against rotation. 70 A plug 45 is threaded into one end of chamber 28 for forming a removable closure for the end of said chamber 28, plug 45 being apertured, as at 46, for receiving a detent-pin.

The inner end of the rod 30 is preferably 80 bored centrally longitudinally and incloses a coiled spring 47, pressing the end of a piston-rod 48, said piston-rod carrying at its outer end piston-head 49. The spring 47 is preferably relatively weak and serves normally to 85 maintain the head 49 spaced a relatively short distance from the end of the rod 30.

In practice when the parts are being removed the rod 30 is projected into the chamber 29 to its farthest extent, and the chamber 90 28 is filled with preferably steel balls, the bore of plug 40 being also filled and any space within the chamber 29 between plug 40 and the piston-head 49 being also filled with balls. The plug 40 is of course positioned, as indicated in Fig. 2, with its bore 42 turned away from the chamber 29 for preventing communication between the chambers 28 and 29 except through the aperture 37, said aperture 37 being of a diameter equal to or slightly less than twice the diameter of one of the balls within the chamber 28. I find in practice that longitudinal pressure on plunger-rod 30 within the chamber 29 will not force a ball upwardly through the aperture 37 unless 100 the same is made of greater diameter than approximately three times the diameter of a ball, and as the practicing of my invention necessitates the supplying of balls from chamber 28 to chamber 29 and the preventing of the return of such balls I make the aperture 37 of about the size indicated, which is ample to admit the ball from chamber 28 to chamber 29, but will not permit the return of such ball. 115

When the draft mechanism 24 is operated for actuating the parts and applying the bracket-shoes 50, the draw-bars 17 will be spread apart or away from each other, due to movement of one of the levers 18 in one direction and the movement of the other lever 18 in the opposite direction, one of said levers being actuated by the other through the expanding adjuster above described, movement being imparted from one of the levers 18 through arm 25, the balls contained within chamber 29, rod 30, and bar 31 to the other lever 18, whereby the balls within chamber 29 will be pressed together, but in practice I find that said balls do not give way and con- 120 125 130

3

stitute almost a rigid device for transmitting movement. The piston 49 and rod 48 may be omitted and the connection will be practically rigid; but I prefer to employ the said 5 piston in order to admit of a very slight movement. When the act of releasing the brakes takes place, the shoes 50 are held close to or practically slightly touching the wheels 1 by the action of the friction-springs 10 12 and 13, so that the beams 7 7 do not approach each other. If the shoes have been worn by contact with the wheels, the releasing movement of the draft mechanism 24 causes the rod 30 to be pulled out of the casing 27, and a ball will drop from the chamber 28 into the chamber 29 and take up the shape occasioned by the separation of the part of said expanding adjuster, so that when the shoes are again applied the slack, which 20 otherwise would have existed, will have been taken up and the brakes may be applied without any lost motion. This operation may continue until all of the balls in the chamber 28 have been deposited in chamber 29, at which time the shoes 50 will have been worn to such an extent as to be no longer serviceable. To place the parts in serviceable condition, it is only necessary to remove the pin 44, rotate the valve 50 for bringing the bore 42 into register with the chamber 39, and thrust the rod 30 longitudinally into the chamber 29 to the full extent of its movement, said longitudinal movements of the rod 39 causing the balls within the chamber 35 29 to move through the bore 42 and bore 41 in the valve 40 and into the chamber 28. As soon as the balls have been restored to their normal position the valve 40 will be rotated to the position indicated in Fig. 2 and the pin 40 44 replaced, the aperture formed in the valve 40 for the reception of the pin 44 being positioned at one side of the axis of the valve for insuring the proper positioning of the valve when the pin is inserted, it being absolutely 45 necessary to have the end of the chamber 29 closed for producing efficient operation of the parts. The bores 41 and 42 of valve 40 are of course much larger than the aperture 37, said bores being, for instance, four or five 50 times greater than the diameter of one of the balls, so that while a ball cannot be forced upwardly through the aperture 37 by a longitudinal thrust of the rod 30 a number of balls may be readily forced through the bores 55 41 and 42.

The casing 27 is usually made of cast metal; but I have found that by continuous use the balls produce slight indentations in the walls of chamber 29 and destroy the efficiency of 60 the apparatus and make difficult the return of the balls to the chamber 28. In order to obviate this objection, I line the chamber 29 with a preferably steel casing 29'. Of course the casing 29' may be made of any suitable 65 material.

A canvas or other suitable cover 51 incloses the end of the casing 27 entered by the rod 30, said covering 51 being preferably folded the shape of an accordion for admitting of free longitudinal separation of the parts, 70 while effectually preventing admission of dust or other foreign substance to the moving elements or to the balls. For the purpose of facilitating application and retention of the casing 51 the end of the casing 27 is annularly grooved, as at 52, and the bar 31 is similarly grooved, as at 53, the ends of the casing 51 being suitably secured within said grooves. 75

Having thus fully described my invention, 80 what I claim as new, and desire to secure by Letters Patent, is—

1. In a slack-adjuster, the combination with the elements to be adjusted, and means for frictionally, temporarily maintaining said 85 elements in an adjusted position, of a plurality of movable objects adapted to be interposed singly between said elements for permanently maintaining the adjustment thereof. 90

2. In a slack-adjuster, the combination with the elements to be adjusted, means for frictionally maintaining such elements temporarily in an adjusted position, of relatively small elements designed to be interposed by 95 gravity between said adjusted elements. 90

3. In a slack-adjuster, the combination with the elements to be adjusted, and means frictionally sustaining said elements temporarily in an adjusted position, of movable objects designed to be interposed between said 100 adjusted elements, and means for retaining said objects between said elements for permanently maintaining the adjustment thereof. 100

4. A slack-adjuster comprising separable elements and balls designed to be interposed between said elements. 105

5. A slack-adjuster comprising separable elements balls designed to be interposed between said elements and a casing for containing 110 said balls when interposed between the elements. 110

6. In a slack-adjuster the combination with the parts of a machine between which slack is to be taken up; of a plurality of balls 115 designed to be interposed by gravity between said parts for taking up the slack thereof. 115

7. A slack-adjuster comprising separable elements and friction means for retaining said elements in given position and balls designed to be interposed between said elements. 120

8. In a slack-adjuster, the combination with an element, of a second element movable with respect thereto, adapted to take up 125 slack and balls designed to be interposed between said elements. 125

9. In a slack-adjuster, the combination with an element, of a second element movable with respect thereto, a lever pivotally 130

- engaging said second-mentioned element, means for producing friction at the point of said pivot and movable objects adapted to be interposed between said first and second 5 mentioned elements.
10. In a brake-slack adjuster, the combination with a brake apparatus, of levers pivotally connected thereto, means for producing friction of the pivots of said levers and 10 means for interposing balls between said levers for taking up slack of the parts connected with the levers.
11. In a brake-slack adjuster, the combination with a brake apparatus, of levers pivotally connected therewith, means for producing friction at the point of said pivots, elements movable with respect to each other, interposed between and pivotally connected with said levers, means for producing friction 15 at the points of said last-mentioned pivots, and means for interposing balls between said movable elements.
12. An expanding adjuster comprising a casing, a rod extending into same and balls 20 designed to be introduced by gravity in said casing.
13. An expanding adjuster comprising a casing, a rod movable longitudinally therein, a longitudinally-movable piston carried by 25 said rod and means for introducing balls into the casing.
14. An expanding adjuster, comprising a casing, a rod movable longitudinally therein, a spring-pressed piston carried by said rod 30 within said casing and means for introducing balls into the casing.
15. An expanding adjuster, comprising a casing formed with a plurality of chambers, a rod movable within one of said chambers and 35 balls carried within the other said chambers, an aperture being formed in the wall between the chambers.
16. An expanding adjuster, comprising a casing formed with upper and lower chambers, a rod movable within the lower chamber and 40 balls arranged within the upper chamber, an aperture being formed in the wall between said chambers.
17. An expanding adjuster, comprising a 45 casing, having a plurality of chambers, a rod movable within one of said chambers and balls within the other chamber, a passage being formed in the wall between said chambers of a size sufficient for admitting of the 50 moving of balls from the second-mentioned chamber to the first-mentioned chamber but preventing the return of such balls under compression by said rod.
18. An expanding adjuster, comprising a 55 casing formed with an upper and a lower chamber, a rod movably mounted in the lower chamber, balls in the upper chamber, an aperture being formed in the wall between the upper and lower chambers for preventing 60 the discharge of balls from the upper chamber to the lower chamber by gravity and means for facilitating return of said balls to the upper chamber.
19. An expanding adjuster, comprising a 65 casing provided with a plurality of chambers, a rod movably mounted in one of said chambers, balls arranged in the other of said chambers, an aperture being formed in the wall between said chambers, of a diameter greater than the diameter of one of the balls and less than twice the diameter of such ball.
20. An expanding adjuster having an upper and lower chamber, a rod movably mounted in the lower chamber and balls arranged in the upper chamber, an aperture being formed in the wall between said chambers, of a size admitting of discharge of balls by gravity from the upper chamber into the lower chamber and preventing return of said balls and a valve for permitting return of the 75 balls from the lower to the upper chamber.
21. An expanding adjuster, comprising a 80 casing formed with an upper and a lower chamber, a rod movably mounted in the lower chamber, balls arranged in the upper chamber, an aperture being formed in the wall between said chambers for permitting of discharge of balls by gravity from the upper to the lower chamber, and a valve arranged at the end of the lower chamber and normally 85 closing said chamber designed to be operated for permitting return of the balls from the lower chamber to the upper chamber.
22. An expanding adjuster, comprising a 90 casing having an upper and lower chamber, a rod movably mounted in the lower chamber, an aperture being formed in the wall dividing 95 said upper and lower chambers and means in said upper chamber adapted to move by gravity through said aperture into the lower chamber for taking up excess of movement of said rod.
23. An expanding adjuster comprising a 100 casing, having a plurality of chambers, a rod movably mounted in one of said chambers, balls disposed in the other of said chambers, an aperture being formed in the wall between the chambers for admitting balls from the second-mentioned chamber to the first-mentioned chamber and a valve formed with a 105 bore communicating with the ball-containing chamber and formed with a second bore communicating with the first bore and adapted to be positioned in register with the rod-containing chamber for permitting return of the 110 balls from the rod-containing chamber to the ball-containing chamber.
24. An expanding adjuster comprising a 115 movably-mounted rod, a casing inclosing the same and means for supplying balls between 120 said rod and the end of said casing.
25. An expanding adjuster comprising a 125 longitudinally-movable rod, a casing surrounding the same, an open-ended chamber formed in said casing and communicating 130

with the rod-surrounding portion of the casing, means carried by said chamber, designed to contact with said rod for preventing approach thereof toward the end of the casing, 5 a closure for the end of said chamber and an accordion casing inclosing said rod and the open end of said casing.

26. An expanding adjuster comprising a movably-mounted rod, a casing surrounding 10 the same, a hardened lining for said casing

and means for introducing relatively small movable elements between said rod and casing.

In testimony whereof I affix my signature in presence of two witnesses.

WILLIAM G. PRICE.
